The ornamental design for a single-panel triage assessment tag, as shown and described.

DESCRIPTION

The application file contains at least one drawing executed in color. Copies of this application with color drawing(s) will be provided by the United States Patent and Trademark Office upon request and payment of the necessary fee.

The sole FIGURE is a view of a single-panel triage assessment tag, showing my new design.

The broken lines on the left side and bottom represent the boundaries of the claimed portion of the design and form no part thereof. All other broken lines within the boundaries form part of the claimed design.
